US00D630731S

(12) **United States Design Patent**
Schmutzer et al.

(10) **Patent No.:** **US D630,731 S**
(45) **Date of Patent:** **** Jan. 11, 2011**

(54) **INFUSION MANAGEMENT SYSTEM
HOLDER**

(75) Inventors: **Stephen E. Schmutzer**, Fort Collins, CO (US); **Mark Henault**, Westminster, CO (US)

(73) Assignee: **Firefly Medical, Inc.**, Fort Collins, CO (US)

(**) Term: **14 Years**

(21) Appl. No.: **29/355,328**

(22) Filed: **Feb. 5, 2010**

(51) **LOC (9) Cl.** **24-02**

(52) **U.S. Cl.** **D24/128**

(58) **Field of Classification Search** D24/127-130; 248/125.8, 121, 129; 135/66-67; 5/86.1; 604/905; D12/130
